UNITED STATES PATENT OFFICE.

JOSEPH G. WIDHELM, OF FREMONT, NEBRASKA.

TANK-HEATER.

1,273,560.

Specification of Letters Patent. Patented July 23, 1918.

Application filed November 7, 1917. Serial No. 200,767.

To all whom it may concern:

Be it known that I, JOSEPH G. WIDHELM, a citizen of the United States, residing at Fremont, in the county of Dodge and State 5 of Nebraska, have invented certain new and useful Improvements in Tank-Heaters, of which the following is a specification.

This invention relates to heaters for stock-watering tanks and one object of the 10 invention is to provide a novel construction of heater which will permit the same to be submerged and rest upon the bottom of the tank and expose an extensive heating surface to the water in the tank so that it 15 will be prevented from freezing and will be maintained at the proper temperature for stock-watering purposes. A further object of the invention is to provide a novel construction which will afford means for 20 cooking feed for stock at the same time that the water in the tank is kept in proper condition for use. Other and incidental objects of the invention will appear as the description thereof proceeds.

25 The invention is illustrated in the accompanying drawings, in which:

Figure 1 is a perspective view of my improved heater;

Fig. 2 is a plan view of the same;

30 Fig. 3 is a central vertical longitudinal section;

Fig. 4 is a transverse section on the line 4—4 of Fig. 3;

Fig. 5 is a detail perspective view of the 35 door or closure for the heating chamber.

In carrying out my invention, I employ a body which is preferably a single casting presenting a vertical hollow column or chamber 1, from the lower portion of which 40 a heating chamber 2 extends laterally. The column 1 should be of sufficient height to extend above the water level and the top of the heating chamber should present a flat surface 3, as shown. The bottom 4 of the casting extends laterally beyond the 45 column 1 to constitute the bottom plate of the heating chamber, and, upon the under side of said bottom plate, are lugs or feet 5, which are adapted to rest upon the bottom 50 of the tank and thereby support the bottom of the heater in spaced relation to the same so that the water may circulate under the heater freely and receive heat therefrom. The wall 6 of the heating chamber 55 is approximately semicircular in horizontal section and is, in effect, a continua-

tion of the side walls of the column connected by an arcuate wall, which latter diverges upwardly from the column and terminates at the bottom wall of a lateral extension 7 of the heating chamber, as shown clearly in Fig. 3. The outer end of the lateral extension is arcuate, as shown most clearly in Fig. 2, and adjacent this arcuate extremity an opening 8 is provided in the 60 top plate 3 to receive a smoke pipe or escape flue 9. This smoke pipe or escape flue should, of course, extend upwardly so that its height will be at least equal to the height of the column 1 and will permit the 65 escape of smoke and other products of combustion into the open air above the water. 70

It will be readily noted that the body is of such form as to bring its walls close around the burner or heating element with 75 the result that the walls will be brought to a high temperature and will radiate heat for a considerable period after the fire has been extinguished. Moreover, the heat will tend to concentrate in the lateral extension 80 of the heating chamber and, as the water is in contact with the bottom and sides of said extension as well as the sides of the heating chamber, the heat will act directly on a large body of the water so that circulation of the same will be quickly set up and the entire volume of water in the tank 85 warmed and prevented from freezing.

The upper end of the column 1 is preferably closed by a cover 10 having a damper 90 11 therein whereby the flow of air to the heating chamber may be regulated, and in one edge of this cover is a notch 12 through which a fuel supply pipe 13 may pass. The fuel supply pipe passes downwardly through 95 the column 1 to a point near the bottom thereof, where it is turned toward the heating chamber and passes through a notch 14 near the lower end of a partition 15 which is formed integral with the side walls of the 100 column and constitutes the inner wall of the heating chamber, the said partition having a large opening 16 formed therein to accommodate a door or closure 17. The said door or closure is provided with a notch or opening 18 in its lower edge so that air may pass under the door to the heating chamber and feed the burner 23 provided within said chamber on the end of the fuel supply pipe. 105 On the inner face of the door 17, reinforcing ribs 19 are provided and these ribs are adapted to fit against the side walls of the 110

opening 16 in the partition so as to frictionally engage the same and thereby aid in holding the door in position, it being understood that the lower end of the door will 5 rest upon the bottom plate 4 of the main casting. At its upper extremity, the door 17 is provided with a handle 20 and below said handle and near the same, an inspection opening 21 is provided so that the condition 10 of the flame may be noted at any time.

From the foregoing description, taken in connection with the accompanying drawings, it will be seen that I have provided an exceedingly simple heater which may be 15 readily placed in a tank or may be moved from place to place. The entire heating portion of the device may be submerged so that a large heating surface will be presented to the water and consequently the 20 water will be effectually prevented from freezing and will be easily maintained in a proper condition for use. When the entire heater is submerged, the lateral extension 7 will, of course, impart heat to the lower portion 25 of the water so that a circulation of water will be set up and the entire body of water will be heated. The flat top 3 may be utilized as a stove top to support vessels containing feed to be cooked or heated. 30 While any desired fuel may be used in the heater, I prefer, and it is intended more particularly to employ kerosene or similar fuel which produces a very intense heat quickly at a low cost and without excessive 35 labor on the part of the user. A cut-off valve may be provided in the supply pipe 13, as indicated at 22, and this valve may be manipulated by removing the cover 10 and then inserting the arm through the column 40 1 so that the intensity of the flame and volume of the heat may be regulated to a nicety. By properly adjusting the damper 11, the flow of air to the burner may be controlled and the proper heat maintained at 45 all times. The fuel supply pipe is disposed at one side of the column 1 so that it will not interfere with an inspection of the burner, the adjustment of the cut-off valve, nor the manipulation of the door 17, and the 50 burner may be inserted or removed without being detached from the pipe. The gases and products of combustion rising from the burner will flow laterally through the extension of the heating chamber and then escape 55 through the smoke pipe 9, as will be readily understood. The flanges 19 on the door 17 aid in preventing warping of the same under the influence of the heat, and the said door may be rocked about its lower 60 edge and caused to lean against the outer wall of the column 1 when the burner and fuel pipe are to be removed or inserted. The main body of the heater is a single casting so that it will be water-tight and its 65 own weight will hold it upon the bottom of

the tank while the entire heating chamber will be submerged and none of the heat units can escape to the air. A large supporting base is provided so that the stability of the device is enhanced, and, by making the main body of a single casting, it is rendered very durable. The device is entirely free of all complicated construction and arrangements and cannot get out of order and may be easily understood and operated by any unskilled person. The vertical member of the heater or column 1 constitutes an air chamber for supplying the air necessary to support combustion to the heating chamber and this air is caused to enter the heating 70 chamber below the burner so that it will properly commingle with the oil or other fuel and produce the desired flame, the formation of soot being avoided so that the efficiency of the heater is not impaired. The 75 said vertical member 1 also constitutes an inspection chamber through which the condition of the flame may be observed and accommodates the user's arm when it is desired to shift the door 17 or set the cut-off 80 valve. As the heating chamber is entirely submerged, the operation of the device is not affected by sudden drafts or strong winds which tend to destroy the efficiency 85 of heaters heretofore employed. The device 90 may also be set up in out-buildings where a mild heat is desired at a low cost and without danger of conflagration.

Having thus described the invention, what is claimed as new is:

1. A device for the purpose set forth consisting of a body having a vertically disposed air supply chamber and a heating chamber extending laterally from one side of the said air supply chamber, a partition 100 between the two chambers having an opening therethrough and a notch in one side of said opening, a fuel supply pipe leading downwardly through the air supply chamber and extending laterally through the said 105 notch to support a burner within the heating chamber, a closure for the opening in said partition having a recess in its lower end, and a cover for the air supply chamber provided with a regulating damper and having 110 a notch in one edge to accommodate the fuel supply pipe.

2. A device for the purpose set forth comprising a body having an air supply chamber and a heating chamber extending laterally from one side of the said air supply chamber, a partition between the two chambers having an opening therethrough, and a closure for said opening provided with ribs 115 on one face near its side edges adapted to extend through and frictionally engage the sides of the opening, said closure resting on the bottom of the body and having a notch in its lower end.

3. A device for the purpose set forth com- 120
